UNITED STATES PATENT OFFICE.

JAMES WHITNEY BARNES, OF LAKE CHARLES, LOUISIANA.

APPARATUS FOR DESTRUCTIVE DISTILLATION.

1,208,453.

Specification of Letters Patent. Patented Dec. 12, 1916.

Application filed February 15, 1916. Serial No. 78,413.

To all whom it may concern:

Be it known that I, JAMES W. BARNES, a citizen of the United States, and a resident of Lake Charles, in the parish of Calcasieu and State of Louisiana, have invented certain new and useful Improvements in Apparatus for Destructive Distillation, of which the following is a specification.

My invention relates to improvements in apparatus for destructive distillation, especially the destructive distillation of wood, and it consists in the combinations, constructions, and arrangements herein described and claimed.

An object of my invention is to provide a device by means of which the destructive distillation of wood or other similar organic bodies may be carried out with greater economy than heretofore.

A further object of my invention is to provide an apparatus of the type described in which the heat may be controlled, thereby eliminating the burning of the product, the formation of products with objectionable odors, and making, in fact, a more uniform product.

A further object of my invention is to provide a device from which the various products may be removed, as they are generated.

A further object of my invention is to provide a device which may be operated at ordinary atmospheric pressure.

Other objects and advantages will appear in the following specification, and the novel features of the invention will be particularly pointed out in the appended claims.

My invention is illustrated in the accompanying drawings forming part of this application, in which—

Figure 1 is a sectional view of the retort, a condensing tank being shown in side elevation. Fig. 2 is a plan view of the apparatus, and Fig. 3 is a plan view of the lower portion of the apparatus, the retort being shown in section.

In carrying out my invention I provide a furnace 1 having flues 2 which lead therefrom. Disposed above the furnace is a retort 3 which is surrounded by a casing 4 made of heat insulating material, the space between the casing and the retort being for the products of combustion which tend to heat the retort and to effect the destructive distillation. At 5 I have shown a cold air chamber.

Extending from the top of the retort is a

pipe 6 for carrying off vapors and gases. At 7 is shown a condenser which is connected with a similar condenser 8, this being connected with the condensers 9 and 10, so that the sets 7, 8, 9, and 10 are arranged in series. At the bottom of the retort 3 is a pipe 11 which leads to a tar still 12. A pipe 13 leads from the top of the latter to a condenser 14, this condenser 14 being one of a set of condensing tanks 14, 15, 16, and 17 which are also connected in series.

At 18 and 19 I have shown two tanks, one being connected with the condenser 10 by means of the pipe 20, and the other being connected with the condenser 17 by means of the pipe 21. Both of these tanks 18 and 19 are connected with an exhaust fan or similar suction apparatus 22. The latter communicates by means of a pipe 23 with a gas bell 24. A branch pipe 25 leads to a condensing pump 26 having communication with a condensing cylinder or tank 27. The latter is connected by means of the pipes 28 and 29 with a cooling coil 30 disposed in the retort 3, a return pipe 31 leading to the condensing pump. As will be seen from Fig. 1, branch pipes 32 and 33 lead from the pipe 29 to the condensing coils or cooling coils 34 and 35 which are disposed in the tanks 17 and 10 respectively.

From the foregoing description of the various parts of the device, the operation thereof may be readily understood.

We will assume that the material to be operated upon is pine wood, although the apparatus is not confined to any particular material. The material having been placed in the retort 3, a fire is started in the furnace. The fuel for this fire may be gas or solid fuel. The products of combustion pass up the flues 2 and heat the retort. The following products are formed in the destructive distillation of pine wood, in the order named: 1. Water with a small quantity of acid. 2. Various grades of turpentine. 3. Acid. 4. Pine oil. 5. Rosin spirits. 6. Rosin oil. 7. Gas, which consists largely of carbon dioxid and carbon monoxid. 8. A residue of coal.

The volatile products pass through the pipe 6 first into the condenser 7 where the heavier portions of the volatile products are condensed, the lighter portions passing successively through the condensers 8, 9, and 10, the gases losing heat in their passage and the products condensing out in the va-

rious condensers in the order of their specific gravities. It will be noted that the condenser 10 is provided with a cooling coil. The means by which this coil is operated, will be explained later. The gas passes through the pipe 20 and into the tank 18. This tank, as well as the tank 19, contains water in which chemicals for purifying the gas may be held. From the tanks 18 and 19, the gas is drawn by the exhaust 22 and is passed through the pipe 23.

The gas may be forced into the gas bell or may be passed directly to the gas condensing pump 26 and from there passed into the condensing cylinder 27. From here the gas may pass through the pipe 29 to the cooling coils 30. For this purpose I provide the valves 27^a and 27^b, see Figs. 1 and 3. The cooling coils 30 are operated on the principle of cooling by expansion, for when the condensed gas is permitted to expand in these coils, the gas absorbs a great deal of the heat, thus cooling off the retort. Since these cooling coils 30 are under the direct control of the operator, it will be seen that the heat in the retort may be controlled very accurately. It will be noted that the condensing cylinder 27 is also connected by means of the pipe 29 with the cooling coils 34 and 35 in the tanks 17 and 10, so that these cooling coils may also be controlled. The cooling coil 30 in the retort 3 and the cooling coils 34 and 35 in the tanks 17 and 10 have exhaust pipes 31 which connect with a common exhaust pipe 32. The pipes 29 leading to the coils 30, 34 and 35 are cold pipes while the pipes 31 are the hot pipes.

During all of the process of distillation from the beginning to the end, tar is produced, and this tar is withdrawn through the pipe 11 and passes into the tar still, from which the vapors may be taken by the pipe 13 into the series of condensers 14, 15, 16, and 17. The operation of these condensers is similar to that already described in connection with the condensers 7 to 10 inclusive, the heavier products condensing in the first condensers and the gas finally passing from the condenser 17 into the tank 19, and thence being drawn off by the fan or suction member 22.

The exhaust fan is in operation during the entire process. By the use of this exhaust fan I am enabled to effect the distillation of certain products at a lower pressure than ordinary.

The gas refining tanks serve a double function, or rather, a triple function. In the first place, they tend to wash the gas, that is to say, they abstract from the gas certain products which are soluble in the water thereby rendering the gas purer. The soluble products thus extracted may be recovered in the form of by-products which are valuable, and thus the tanks are avail-

able for the formation of new products. There is a third use, however, for the tanks 18 and 19. It will be observed that the gaseous products which pass through the pipe 6 eventually find their way into the tank 18, while the products which pass up through the pipe 13 may find their way into the tank 19. By regulating the height of the water in the tanks 18 and 19, I am enabled to regulate the proportion of gas passing through the exhaust fan 22 from one series or the other of the condensers. Thus, if there is a relatively small amount of water in the tank 19, then the greater portion of the gas will be drawn through the tank 19 than through the tank 18. These tanks, therefore, form virtually governors for controlling the amount of gas drawn through the two branches.

In Fig. 1 I have shown the gas bell diagrammatically, but it will be understood that any form of bell may be used. I have also illustrated the device as being heated by a furnace having grate bars for solid fuel, but the gas from the gas bell 24 might be piped into the furnace so as to heat the retort without departing from the spirit and scope of the invention.

In this device it is seen that I have provided an arrangement in which the heat is controlled, the removal of the products from the retort being accomplished as fast as the products are formed. The cooling of the retort at will prevents the burning of certain products of burn odors. There is another feature which adds to the desirability of this arrangement, and that is that after the retort has been used, that is to say, when the process is completed, the retort may be cooled so that the contents of the retort may be removed and the retort again placed in operation. This can be done in much less time than in the ordinary process where the retort is allowed to cool off gradually.

I claim:—

1. The herein described apparatus for destructive distillation which comprises a retort, means for heating the same, means at one end of the retort for carrying off the vapor, means for fractionally condensing the vapor, means at the opposite end of the retort for carrying off the liquid products, means for heating the liquid products, means for condensing fractionally the heated vapor from the liquid products, a common gas bell, a suction device disposed between said common gas bell and each set of condensers for withdrawing the gas from each of the sets of condensers, and means for regulating the temperature of the retort.

2. The herein described apparatus for destructive distillation which comprises a retort, means for heating the same, means at one end of the retort for carrying off the

- vapor, means for fractionally condensing the vapor, means at the opposite end of the retort for carrying off the liquid products, means for heating the liquid products, 5 means for condensing fractionally the heated vapor from the liquid products, a common gas bell, a suction device disposed between said common gas bell and each set of condensers for withdrawing the gas from 10 each of the sets of condensers, means for regulating the temperature of the retort, and means for cooling certain of said condensers.
3. The herein described apparatus for de- 15 structive distillation, which comprises a retort, means for heating the retort, a pipe at the top of the retort for conveying away vapors of distillation, a pipe at the bottom of the retort for conveying away liquid 20 products, a set of condensers for fractionally condensing the vapor products, means for vaporizing the liquid products, a set of condensers for said last named products, an exhaust fan having communication with 25 each set of condensers, a gas bell connected with said exhaust fan, a gas condenser having communication with said gas bell and with said exhaust fan, a cooling coil dis- posed within the retort and having com- 30 munication with said gas condensing device, and means for controlling the flow of gas into said cooling coil.
4. The herein described apparatus for de- 35 structive distillation, which comprises a re- tort, means for heating the same, means at one end of the retort for carrying off the vapor, means for fractionally condensing the vapor, means at the opposite end of the retort for carrying off the liquid products, means for heating the liquid products, 40 means for condensing fractionally the heated vapor from the liquid products, a common gas bell, a suction device disposed between said gas bell and each set of condensers for withdrawing the gas from each 45 set of condensers, and means for regulating the temperature of the retort and of certain of said condensers, said means comprising a cooling coil within the retort, a cooling coil for each of the said condensers, a gas con- 50 denser pump, and a condenser cylinder communicating with said gas bell and said suction device, and cooling pipes connecting said condenser cylinder with the cooling coils in said retort and in said condensers. 55

JAMES WHITNEY BARNES.
